WILLIAM H. GROVE, OF PHILADELPHIA, PENNSYLVANIA.

Design No. 4,978, dated June 6, 1871.

DESIGN FOR A SHOW-CASE.

The Schedule referred to in these Letters Patent and making part of the same.

I, WILLIAM H. GROVE, of Philadelphia, county of Philadelphia, State of Pennsylvania, have invented a Design for a Show-Case, of which the following is a specification.

In the accompanying drawings—

Figure 1 is a perspective view of a show-case made in accordance with my design, and

Figure 2 is an end view of the same.

A and B represent the front and back of the case;

C C, the opposite ends; and

D and E, the top and bottom.

The front and back of the case are inclined in opposite directions, and at the same or different angles;

the ends C C are vertical, and the top and bottom are horizontal and parallel; or the top may be slightly inclined, as in ordinary show-cases.

I claim—

The design for a show-case with inclined sides and vertical ends, substantially as shown and described.

In testimony whereof I have signed my name to this specification in the presence of two subscribing witnesses.

W. H. GROVE.
